UNITED STATES PATENT OFFICE.

AARON COLEMAN, OF NEW YORK, N. Y.

DESIGN FOR A SUSPENDER-END.

SPECIFICATION forming part of Design No. 31,728, dated October 24, 1899.

Application filed September 2, 1899. Serial No. 729,392. Term of patent 7 years.

To all whom it may concern:

Be it known that I, AARON COLEMAN, a citizen of the United States, residing in the borough of Manhattan, city, county, and State of New York, have invented and produced a new and original Design for a Suspender-End, of which the following is a specification.

In the accompanying drawing I have illustrated a suspender-end A embodying my design.

The leading or essential feature of my design consists of a double loop A', the ends of which are adapted to be connected with the webs of the shoulder-straps of the suspender.

15 A part c, through which the double loop A' passes, carries the buttonhole-strap C.

It is evident that the design is applicable equally to the back or front of suspenders and to articles of a like nature.

Having described my invention, what I claim as new, and desire to secure by Letters Patent, is—

The design for a suspender-end, substantially as herein shown and described.

In testimony whereof I have signed my name to this specification in the presence of two subscribing witnesses.

AARON COLEMAN.

Witnesses:

J. EUGENE SONNER,
H. COUTANT.
